DESIGN FOR A DRESS ENSEMBLE

John Tuman, New York, N. Y.

Application April 28, 1938, Serial No. 76,775

Term of patent 3½ years

To all whom it may concern:

Be it known that I, John Tuman, a citizen of the United States of America, residing in city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view thereof.

Fig. 3 is a fragmentary view of the front dress portion of the dress ensemble.

Fig. 4 is a rear view of Fig. 3.

My design is characterized by the specific embroidery on the collar and front dress portions of the dress as shown, in combination with the specific embroidery on the pockets of the jacket portion of the ensemble.

I claim:

The ornamental design for a dress ensemble substantially as shown and described.

JOHN TUMAN.
